CLAIM

The ornamental design for a flashlight in the shape of a key, as shown and described.

DESCRIPTION

FIG. 1 is a rear side perspective view of the flashlight in the shape of a key, showing my new design;

FIG. 2 is a front side perspective view thereof;

FIG. 3 is a rear view thereof;

FIG. 4 is a front view thereof;

FIG. 5 is a left side view thereof;

FIG. 6 is a right side view thereof;

FIG. 7 is a top view thereof; and,

FIG. 8 is a bottom view thereof.

The broken lines show portions of the article which form no part of the claimed design.
